HAMMOCK.

Application filed February 21, 1927. Serial No. 169,707.

This invention relates to hammocks of a kind more particularly useful as suspensions incidental to weighing infants.

The object of my invention is to provide a hammock of the type referred to having capacity to adapt itself to the configuration of the infant so as to comfortably support the latter in a state of complete relaxation during weighing; which is amply reinforced against collapsing, but notwithstanding, extremely light so as to be negligible in so far as weight is concerned; which is susceptible of folding into a compact compass; which is easily laundered for maintenance in a sanitary condition; which is devoid of all hard or metallic fittings likely to injure the infant; and which is conducive to very economic manufacture from textile fabric.

One way in which the foregoing advantages may be realized in practice will be readily apparent from the detailed description hereinafter of the typical embodiment of my invention depicted in the drawings, whereof Fig. I shows the manner in which the hammock is used.

Fig. II shows the fabric blank from which the hammock body is made.

Fig. III shows the result of a cutting and sewing step whereby the ends of the blank are fashioned to taper configuration; and,

Fig. IV shows the back of the finished hammock.

In carrying out my invention, I prepare, from suitable textile fabric, for example soft flannel, a rectangular blank 10 of the proportions shown in Fig. II. Such blank I first **V** cut longitudinally inward to equal distances from the center of opposite ends as graphically indicated in dotted lines at 11, 11, and thereupon unite the contiguous edges of the cuts by sewing, as shown at 12, 12 in Fig. III, with incidental formation of fashioned taper end prolongations 13, 13 in direct continuation of a full-width medial area 14. The blank 10, thus modified, constitutes the hammock body, which, in finishing, I preferably reinforce at the back as shown in Fig. IV, with comparatively narrow fabric tape, applying the same perimetricaly about the

edges of the angularly-recessed or "bight" ends as at 15, along the seams 12, 12 as at 16, crosswise between the end prolongations 13, 13 and the medial area 14 as at 17, and diagonally of said medial area as at 18. At opposite sides I equip the hammock with suspension straps 19 which may be conveniently of

the same tape as that used in reinforcing. The ends of the straps 19 are anchored by sewing at the junctures between the perimetrical, cross and diagonal strips 15, 17, 18 as shown in Fig. IV, and at their centers have loops 20 formed by folding of the tape and sewing the superposed strands together inward of the folds as at 21. A hammock thus made is obviously strong, very light as regards weight, easy to launder and readily foldable into a compact package. In use, it is spread out flat upon a table, the infant placed thereon, and the loops 20 of the straps 19 engaged by means of a conventional type of spring catch ring 22 with the ring R on the plunger of a weighing scale S as shown in Fig. I, whereupon the whole may be suspended in one hand while the scale reading is being taken. It is to be particularly observed that by virtue of its perimetrical and diagonal reinforcement, the medial area 14 is effectively braced against collapsing in the longitudinal direction, but notwithstanding, adapts itself readily to the body of the infant. Moreover, as a consequence of being fashioned, the end prolongations 13, 13 take an upward inclination as shown in Fig. I, thereby serving to support the head and legs of the infant somewhat above the level of the body so that the necessity for "prop" pillows or cushions for this purpose is entirely dispensed with. The infant is thus supported in absolute equilibrium and comfort with its back underslung and well braced against strain or fatigue, and its head and feet high.

It is furthermore to be noted that by provision of the permanent central loops 20 at the centers of the suspension straps 19, the latter are prevented from slipping or riding in the ring R of the weighing scale S, and the hammock thus rendered stable against the possibility of tilting incidentally to weighing an active baby. Inasmuch as the infant is effectively "harnessed in", it cannot slip or fall out of the hammock irrespective of unruliness and is therefore protected in all ways from injury.

Having thus described my invention, I claim:

1. A hammock of the character described consisting of a rectangular piece of textile fabric having opposed **V**-cuts centrally of its opposite ends and extending longitudinally inward for equal distances, the contiguous edges of said cuts being seamed together so as to give the hammock a full-width medial

- area and correspondingly fashioned taper-prolongations with eight ends, the whole fabric piece reinforced by flexible tape attached about the perimetric edges, along the seamed cuts aforesaid, across the region of mergence between the medial area and the fashioned taper-prolongations, and diagonally of said medial area; and means whereby the hammock may be suspended.
- 10 2. A hammock of the character described consisting of a rectangular piece of textile fabric having opposed V-cuts centrally of its opposite ends, the contiguous edges of said cuts being seamed together so as to give the hammock a full-width medial area and fashioned taper-prolongations; with eight ends; the whole reinforced by flexible tape attached about the perimetric edges, along the seamed cuts aforesaid, across the region of mergence between the medial area and the fashioned taper-prolongations, and diagonally of said medial area; and suspension straps of flexible tape with loops formed at their centers, said straps being attached at the ends to the junctures between the perimetric, cross and diagonal reinforcements.
- 15 3. A hammock of the character described consisting of a rectangular piece of textile fabric having opposed V-cuts centrally of its opposite ends, the contiguous edges of said cuts being seamed together so as to give the hammock a full-width medial area and fashioned taper-prolongations; with eight ends; the whole reinforced by flexible tape attached about the perimetric edges, along the seamed cuts aforesaid, across the region of mergence between the medial area and the fashioned taper-prolongations, and diagonally of said medial area; and suspension straps of flexible tape with loops formed at their centers, said straps being attached at the ends to the junctures between the perimetric, cross and diagonal reinforcements.
- 20

perimetric, cross and diagonal reinforcements.

25

3. A hammock of the character described consisting of a rectangular piece of textile fabric having opposed V-cuts centrally of its opposite ends, the contiguous edges of said cuts being seamed together so as to give the hammock a full-width medial area and fashioned taper-prolongations with eight ends; the whole reinforced by flexible tape attached about the perimetric edges, along the seamed cuts aforesaid, across the region of mergence between the medial area and the fashioned taper-prolongations, and diagonally of said medial area; and suspension straps of flexible tape with loops formed at their centers, said straps being attached at the ends to the junctures between the perimetric, cross and diagonal reinforcements.

In testimony whereof, I have hereunto signed my name at Allentown, Pennsylvania, this 14th day of February, 1927.

GERTRUDE KLINE.
